UNITED STATES PATENT OFFICE

2,633,236

COVER

Herbert W. Hempel, Belleville, Ill., assignor to
Marsh Stencil Machine Company, Belleville,
Ill., a corporation of Illinois

Application May 31, 1949, Serial No. 96,320

1 Claim. (Cl. 206—15.1)

1

The present invention relates generally to closure devices, and more particularly to a cap for a brush or the like which is formed to facilitate the capture of all of the bristles without damage to them.

In summary, the present invention comprises a cylindrical cap open at one end which includes a notch or bristle entry gap of selected form and depth in the wall opening into the mouth. As is more particularly shown in the drawing and described in the following specification, the boundary walls of the notch may be in the normal plane of the cap or they may be formed inset or outset as desired. In applying the cap to cover the bristles of a brush, the cap is rotated as it is installed in order to pass the bristles into the notch which deflects them into the interior of the cap. A modified construction contemplates a projecting tongue.

It is desirable to cap the bristles of many types of brushes, particularly those used sporadically during a work operation or used from time to time. One example is the fountain brush used to soap pipe joints to detect leaks, the capping of such preventing soapy liquid from getting on the support on which the brush is placed while not being used, such as the tool box or worker's pocket. Another example is the stencil marking fountain brush when used with ink which cakes or hardens on the bristles if the brush is left uncleared and in the open air. A substantially sealing cap disposed over such coated bristles prevents caking. However, standard caps are awkward to apply, and damage the brushes through clipping off "stray" bristles each time they are applied.

Therefore, an object of the present invention is to provide a novel cap for bristle brushes and the like which includes a notch, tongue, or the like, for facilitating the trapping of the bristles of the brush without damage to them.

Another object is to provide a novel cap for bristle brushes or the like which is of cylindrical or other forms, open at one end, and which is cut away, extended or otherwise formed at one portion of the free edge to provide a trap or deflector for bristles when the cap or brush is rotated one relative to the other in the bristle encasing operation.

Another object is to provide a novel method of entrapping the bristles of a brush in a snugly fitting cap so that no damage is caused to the bristles during the encasing operation.

Another object is to provide a novel cap construction incorporating a notch in the side which

2

receives stray bristles during an encasing action, and which, in the relative rotation of the cap and brush, lead the stray bristles into the interior of the cap without damage to them.

5 Other objects are to provide a novel cap for bristle brushes which is inexpensive, which may be quickly applied to the bristles of a brush, and which adequately covers the bristles of a brush to prevent contact thereof with the surface upon 10 which the brush may be disposed and to substantially seal off the air.

The foregoing and other objects and advantages are apparent from the following description taken with the accompanying drawing, in 15 which:

Fig. 1 is a side elevational view of a cap formed in accordance with the teachings of the present invention, being applied to the bristles of a fountain brush, the handle of the brush being 20 broken away for conservation of space;

Fig. 2 is a plan view of the cap and brush portion shown in Fig. 1;

Fig. 3 is a view showing the cap in place on the brush covering the bristles;

25 Fig. 4 is a cross-sectional view on substantially the line 4—4 of Fig. 3;

Fig. 5 is a side elevational view of a modified cap;

Fig. 6 is a cross-sectional view on substantially 30 the line 6—6 of Fig. 5;

Fig. 7 is a view similar to Fig. 1, but illustrating a still further modified cap construction;

Fig. 8 is an elevational view of the cap and 35 brush shown in Fig. 7 in fully closed relation;

Fig. 9 is a cross-sectional view on substantially the line 9—9 of Fig. 8;

Fig. 10 is a side elevational view of a still further modified cap; and

40 Fig. 11 is an end view thereof.

Referring to the drawing more particularly by reference numerals, and specifically considering Figs. 1 through 4, 10 indicates generally a cap formed in accordance with the teachings of 45 the present invention. The cap 10 is of cylindrical construction including a cylindrical body 12, a closed end 14, and an open end 16. A V-shaped notch 18 is formed in the body 12 inwardly of the open end 16. Spaced indentations 20 may be provided for a purpose specified below. A fountain brush 22 is shown in association with the cap 10 and includes a handle 24 having a shoulder portion 26 which supports 50 bristles 28.

55 In Figs. 1 and 2, the cap 10 and the brush 22

are shown in a preferred relationship preparatory to trapping the bristles 28 in the cap 10. The bristles 28 are disposed in the notch 18, and either the brush 22 or the cap 10 rotated relative to the other in either direction. When expertly done, the bristles 28 will be fully entrapped within less than a rotation of either the brush 22 or the cap 10. Even a novice can quickly entrap the bristles 28. While a preferred method of entrapping the bristles 28 is illustrated in Figs. 1 and 2, the cap 10 and brush 22 may be moved toward each other on the same axis, and, after a portion of the bristles have entered the cap 10, either the cap 10 or the brush 22 may be rotated relative to the other, whereupon the bristles 28 will be fully entrapped without damage.

In Figs. 5 and 6 is shown a modification of the cap 10 in the form of a cap 30. The cap 30 is similar to the cap 10 with the exception of the shape of a notch 32. The notch 32 has one wall 34 deflected inwardly and a second wall 36 deflected outwardly as is clearly shown in Fig. 6. The form of notch 32 of the cap 30 facilitates bristle trapping, since the outwardly deflected wall 36 serves to more positively trap stray bristles than the corresponding wall of the notch 18 of the cap 10.

In Figs. 7 through 9, there is shown a cap 40 which comprises a further modification of the present invention as initially disclosed in Figs. 1 through 4. The cap 40 includes a notch 42 of shallow depth which is defined by inwardly directed wall portions 44 and a bottom wall portion 46. The cap 40 is shown in association with a fountain stencil brush 48 which includes a hollow handle 50, a bevelled flange 52, and bristles 54. As is clear from Fig. 9, the cap 40 is bevelled at its open end in correspondence to the bevelled flange 52.

In Figs. 10 and 11 is shown a still further modification of the present invention. A cap 60 including a closed end 62 and an open end 64 has a projecting tongue 66 riveted or welded to or formed integral with the cap wall at the open end 64. The tongue 66 includes a bevelled edge 68 which will deflect bristles into the cap 60.

Manifestly, the method of entrapping the bristles of a brush is the same with the caps 10, 30, 40, and 60. The particular cap is rotated relative to the brush, or vice versa, which insures rapid entrapping of the bristles without damage.

It is manifest that the notch in the particular cap may be formed of any desired configuration, such as a half V selected to trap bristles in

clockwise or counterclockwise rotation, and may have the defining walls distorted or not, as desired.

It is clear that there have been provided a novel cap construction and a novel method of applying a cap to the entrapment of bristles which fulfill the objects and advantages sought therefor.

It is to be understood that the foregoing description and the accompanying drawing have been given by way of illustration and example. It is also to be understood that changes in form of the several parts, substitution of equivalent elements or steps, and rearrangement of parts or steps, which will be readily apparent to one skilled in the art, are contemplated as within the scope of the present invention, which is limited only by the claim which follows.

What is claimed is:

In a brush assembly: a brush having a handle with bristles extending outwardly therefrom, the handle having a cylindrical shoulder portion extending axially from the bristle end thereof a predetermined distance, a cap comprising an elongated tubular body closed at one end and open at the other end for receiving both the bristles and the cylindrical shoulder of said brush, said body having a bristle entrapping notch extending from said open end only partially the length of the body, said notch being approximately equal in length to the length of the cylindrical shoulder portion of the brush handle, and the body of the cap adjacent said notch being of a diameter to fit snugly over the cylindrical shoulder portion, whereby the bristles may be disposed in the notch and twisted into the cap, and then may be substantially enclosed within the cap when it is disposed upon the cylindrical shoulder portion.

40 HERBERT W. HEMPEL.
